Non-final Office Action issued in connection with U.S. Appl. No. 29/554,084, dated Dec. 21, 2016.

(Continued)

Primary Examiner — Patricia Palasik*(74) Attorney, Agent, or Firm* — Meunier Carlin & Curfman LLC(57) **CLAIM**

The ornamental design for a heat shrinking machine, as shown and described.

DESCRIPTION

FIG. 1 is a perspective view of my new design;

FIG. 2 is a left-side view thereof;

FIG. 3 is a right-side view thereof;

FIG. 4 is a front view thereof;

FIG. 5 is a rear view thereof;

FIG. 6 is a top view thereof; and,

FIG. 7 is a bottom view thereof.

The broken lines in the drawings depict unclaimed environmental subject matter.

1 Claim, 6 Drawing Sheets---
